UNITED STATES PATENT OFFICE.

ADELBERT R. WICKER, OF DENVER, COLORADO, ASSIGNOR, BY MESNE ASSIGNMENTS,
TO JOSEPH HERMANN, OF CINCINNATI, OHIO.

LOCK-CONTROLLED FUEL-FEED FOR CARBURETERS.

1,374,621.

Specification of Letters Patent.

Patented Apr. 12, 1921.

Application filed February 28, 1919. Serial No. 279,787.

To all whom it may concern:

Be it known that I, ADELBERT R. WICKER, a citizen of the United States, residing at the city and county of Denver, and State 5 of Colorado, have invented certain new and useful Improvements in Lock-Controlled Fuel-Feed for Carbureters; and I do hereby declare the following to be a full, clear, and exact description of the invention, such as 10 will enable others skilled in the art to which it appertains to make and use the same.

This invention relates to controlling means for fluid feed lines, and more especially to an improved lock-controlled fuel- 15 feed for the carbureters of automobiles employing hydrocarbon engines of the internal combustion type.

While the primary aim of the invention is to provide a substantially effective anti- 20 theft attachment for such gas-propelled automobiles, or to guard against the ever-increasing evils of other unauthorized uses of same, still it will be apparent that its field of utility is not necessarily so restricted.

25 For instance, the improvements may be used with any class of automobile, employing a hydrocarbon fuel feed line from a supply tank to the engine, whether the engine be of the internal combustion type or one where 30 the fuel oil is delivered to jet burners for steam generative purposes. Likewise, the invention may well be associated with charge forming devices or the carbureters of any or all of such engines employed in other 35 relations, such as motor vehicles generically whether adapted more especially for land, marine, or aerial propulsion.

It may also be said at the outset that, in carrying out the broader aims of my invention, 40 I do not simply provide an independently operating lock for a cut-off in the fuel supply line, but contrariwise my controlling lock is so operatively associated with the cut-off or valvular element that the latter 45 is directly actuated, into its open and closed positions, conjointly with the positive operation of the lock itself, upon the insertion therein, and actuation in reverse directions as desired, of a properly fitting detachable 50 key.

Other objects and advantages of the detailed construction, assembly and functioning of the combined elements will be so clearly apparent from the following disclosure 55 that it would only be unnecessary and

undesirable repetition to further refer to them initially, and for a more complete conception thereof reference will now be had to the accompanying drawings, illustrating a practical embodiment of the improvements, in which drawings—

Figure 1 is a longitudinal sectional view through a suitably formed metallic casing, with my novel combination of co-operating elements housed therein, the section being 60 taken substantially in the plane of the lines 1—1 of Figs. 2 and 3, with the valvular cut-off member and its actuating lock element shown in elevation, while the bottom screw-plug closure is slightly turned, from 65 its normal position in Fig. 3, to show more effectively the outlet feed ducts thereof in full lines; Figs. 2, 3 and 4 are cross-sectional views of Fig. 1 along the planes of the lines 70 2, 3 and 4, respectively, and looking in the 75 directions of the indicating arrows; and Fig. 5 is a top plan view.

The casing proper is cast from a suitable metal or metallic composition to form an upper and a lower housing 10 and 11, respectively, partially offset relatively to each other, and providing coupling nipples 12 and 13, all of which are suitably bored and threaded where necessary, as will herein-after more fully appear, and in which casing 80 all of the operative elements are housed and effectively sealed, when assembled, against any tampering with.

A partitioning wall 14 extends across the lower portion of the upper housing 10, and 85 is formed with an eccentrically disposed threaded bore 15 therethrough, alining concentrically however with the relatively offset lower housing 11, and which bore 15 merges into a larger one, formed within the 90 thickened wall 16 of the upper portion of the lower housing, thus providing for a lower threaded section 17 and an intermediate packing chamber 18, which latter is 95 preferably smooth-bored.

100 Within this chamber 18, a centrally apertured upper guide-bearing disk 19 is disposed underneath the formed shoulder 20, and in the threaded section 17 there is adjustably mounted an alining centrally apertured lower guide-bearing disk 21, threaded peripherally to also serve as a gland element for compressing a suitable packing material 22, inserted within the chamber 18 which packing material, when thus com- 105 110

pressed, holds the upper guide-bearing disk 19 firmly seated.

Although obviously unessential, the opposed faces of the disks 19 and 21 are preferably dished as shown, and a washer 23 may be applied to the concave face of the lower disk, while the opposite face thereof is formed with spanner sockets 24 for the application of a suitable adjusting implement.

10 The lower portion of the housing 11 is still of larger bore, to snugly contain a replaceable valve seat element, and is internally threaded, as far as necessary to also receive an externally threaded plug closure.

15 The valve seat element is in the nature of a thick peripherally smooth disk 25, having a central port 26 therethrough, of restricted diameter, which in turn is encompassed by a central recess, countersunk 20 from the upper face of the disk and adapted to snugly receive an embedded valve seat 27, of suitable composition, which latter likewise has a central port, in registration with the port 26, the upper end of which 25 forms the seat proper for a conical plug valve element.

The bottom plug-closure is itself of important detailed construction, and not only serves as a support for holding the valve 30 disk 25 rigidly seated, upper and lower washers 28-29 being supplied for the latter but it also auxiliarily provides for a novel method of feeding the oil smoothly, under an even pressure, to the carbureter, instead 35 of by a direct spouting.

This plug-closure consists of a main body portion 30, substantially hollowed out at its underneath side for lightness and finish, and provides the spanner sockets 31, for wrench 40 manipulation, and a sealing flange 32.

Its upper face is recessed with a bowl-like cavity 33, immediately below the port 26, from which bowl leads a plurality of radially declining eduction ports 34, extending 45 through the body portion and terminating at their outer ends in a common delivery channel 35, comprising a circumferential groove formed peripherally of the cylindrical outer surface of the plug, which 50 peripheral groove 35, when the plug is screwed home, registers with the bore of the outlet nipple 13, with all of the radial ducts 34 out of direct registration with the latter, as more clearly seen from Fig. 3.

55 This arrangement establishes a sort of equalizing oil pressure, whereby an even flow of the oil is maintained in its delivery to the carbureter, whether the outlet nipple 13 is directly fitted to the carbureter, which 60 is the preferred practice, or is coupled up therewith through the interposition of a tube coupling 36, which latter sometimes becomes expedient.

37 simply designates the usual tubing

from the oil supply tank, coupled with the 65 inlet nipple 12 of the improved attachment, which nipple opens into a shallow receiving oil chamber 38 formed, within the threaded bore 17, intermediate of the guide-bearing gland 21 and the valve seat element 25. 70 This oil chamber 38 is in controlled communication with the outlet nipple 13, through the several ports or ducts heretofore described, although in Fig. 1, more clearly illustrating same, the flow of oil is 75 cut off, owing to the closed position of the lock-controlled plug-valve, which will now be more particularly referred to.

This element comprises a positively operating unitary member, avoiding all separable spring controlled parts, consisting of a stem 39 reciprocatingly mounted through the alining apertures of the upper and lower guide-bearing disks 19-21, and terminating at its lower end in a conical plug 85 40 coacting with the valve seat 27.

The upper end of the stem is screwthreaded externally, as at 41, for engagement with the threaded bore 15, and is provided with a vertical slot 42, for the reception of the rotary bolt 43 of a suitable detachable-key controlled lock, the locking or unlocking of which rotates the bolt 43 as well, and hence the valve stem 39, coupled therewith. 90

The lock itself being of no essential feature, in its detailed construction, to the invention proper, is simply shown conventionally at 44, having a lower centering disk 45, snugly fitting within the housing 10, the upper covering plate providing a sealing 100 flange 46, and the usual key-barrel 47.

However, the style of lock thus far found most peculiarly adapted for the particular purpose is of the multiple-disk tumbler type, such as a Yale or a Corbin cabinet 105 lock, slightly modified in construction as to provide a rotating engaging pin or bolt element instead of a bolt or pin which is actually shot out of the lock casing.

Also, it may be stated that the threads of 110 the bore 15 and the screw-head 41, engaging therein, are of such a substantial pitch that the rotation of the lock bolt or pin 43, by the turning of the inserted key from locking to unlocking position or vice versa, 115 will actuate the conical plug valve 40 to its relatively full open or closed position, the closing movement being downwardly, with a direct-acting rotary-thrust, in the direction of the flow of the oil, into positive 120 wedging contact with its fibrous valve seat 27, while the opening movement is equally positive in reverse motion upon unlocking the lock as well, there being no indirect actuating means employed whatsoever, in either 125 direction of movement, such as unsatisfactory springs so liable to become broken, weakened, dislodged, or otherwise rendered

defective as to reliable efficiency if not entirely inoperative.

From the foregoing complete disclosure, it is believed that the complete operation 5 will be entirely obvious without further description thereof, it being understood that in Fig. 1 the fuel feed supply line is shown as cut off by the closed position of the plug valve 40, and is maintained locked in that 10 closed position until a proper key is inserted in the lock 44, and operated not only to unlock the latter but also to simultaneously unseat the plug valve, with a positive direct-acting withdrawal movement, 15 for again establishing communication between the fuel oil supply tank and the carbureter.

Finally, the assembling of the various elements of the attachment will be equally 20 obvious, and when so assembled the top or flange plate 46 of the lock may be effectively sealed to the casing by brazing or otherwise to prevent any tampering with the lock proper, while the screw plug closure 25 30, which may or may not be sealed also as desired, provides a ready means for disassembling the valve seating element, for renewing the fibrous seat 27 when required by long wear.

30 Thus it will be seen that my improvements embody a readily attachable appliance for a lock-controlled fuel-feed supply line, preferably applied directly to the carbureter casing itself, as would be indicated 35 by Fig. 5, although an intermediate tubular connection 36, as indicated by Figs. 1 and 3, may obviously be employed where found to be expedient or desirable, the said appliance being not only of simple and light construction and durable and efficient in action, 40 but also a device that is comparatively inexpensive to manufacture and install.

Having now made a full and complete disclosure of a practical embodiment of the 45 invention, it will be understood, however, that I do not limit myself to the exact details as set forth, excepting as come within the purview of the appended claims, when viewed in the light of the disclosure and a 50 fair interpretation of the same; the usual range of equivalents being in contemplation.

What I do claim as patentably novel is—

1. Valve mechanism of the character described, comprising a casing partitioned by 55 a transverse wall, provided with a threaded bore, said wall separating said casing into an upper and a lower housing, the lower housing comprising a partially threaded packing compartment, a valve seating compartment and an intermediate fluid holding 60 compartment, an apertured guide member threaded to engage the screw threads of said packing compartment and forming both an adjustable lower gland for said packing 65 compartment, and a top closure for said

fluid compartment, packing material mounted above said gland, a ported valve seat closing the outer end of said fluid compartment, an inlet for said fluid compartment above said valve seat, and an outlet leading 70 from said casing below said valve seat, a valve stem extending through said gland and said packing and having a screw threaded head engaging with said threaded wall bore, a plug valve carried by said valve stem coacting with said valve seat, and means operable from said upper housing for rotating said valve stem and thereby moving said valve toward or away from its seat, substantially as described. 80

2. Valve mechanism of the character described, comprising a casing partitioned by a transverse wall, provided with a threaded bore, said wall separating said casing into an upper and a lower housing, the lower 85 housing comprising a partially threaded packing compartment, a valve seating compartment and an intermediate fluid holding compartment, an apertured guide member threaded to engage the screw threads of said 90 packing compartment and forming both an adjustable lower gland for said packing compartment, and a top closure for said fluid compartment, packing material mounted above said gland, a ported valve seat 95 closing the outer end of said fluid compartment, an inlet for said fluid compartment above said valve seat, and an outlet leading from said casing below said valve seat, a valve stem extending through said gland 100 and said packing and having a screw threaded head engaging with said threaded wall bore, said head being provided with a transverse slot at its upper end, a plug valve carried by said valve stem and means 105 mounted in said upper housing and engaging said slot for rotating said valve stem and thereby moving said valve toward or away from its seat, substantially as described. 110

3. Valve mechanism of the character described, comprising a casing partitioned by a transverse wall, provided with a threaded bore, said wall separating said casing into an upper and a lower housing, the lower 115 housing comprising a partially threaded packing compartment, a valve seating compartment and an intermediate fluid holding compartment, an apertured guide member threaded to engage the screw threads of said 120 packing compartment and forming both an adjustable lower gland for said packing compartment, and a top closure for said fluid compartment, packing material mounted above said gland, a plug screwed into the 125 lower end of said lower housing and provided with a central chamber on its upper side, an annular passage on its periphery and ducts connecting said central chamber with said annular passage, an axially perfo- 130

- rated disk provided with a valve seat mounted above said plug, said casing being provided with an inlet for fluid located above said valve seat, and an outlet for fluid registering with said annular passage, a valve stem having a screw threaded head engaging said threaded wall bore, said head being provided with a transverse slot at its upper end, a plug valve carried by said valve stem 10 and means mounted in said upper housing and engaging said slot for rotating said valve stem and thereby moving said valve toward or away from its seat, substantially as described.
- 15 4. Valve mechanism of the character described, comprising a casing partitioned by a transverse wall, provided with a threaded bore, said wall separating said casing into an upper and a lower housing, the lower 20 housing comprising a partially threaded packing compartment, a valve seating compartment and an intermediate fluid holding compartment, an apertured guide member threaded to engage the screw threads of said 25 packing compartment and forming both an adjustable lower gland for said packing compartment, and a top closure for said fluid compartment, packing material mounted above said gland, a plug screwed into the 30 lower end of said lower housing and provided with a central chamber on its upper side, an annular passage on its periphery and ducts connecting said central chamber with said annular passage, an axially per- 35 forated disk provided with a valve seat mounted above said plug, said casing being provided with an inlet for fluid located above said valve seat, and an outlet for fluid registering with said annular passage, 40 a valve stem having a screw threaded head engaging said threaded wall bore, a plug valve carried by said valve stem coaxing with said valve seat, and means operable from said upper housing for rotating said 45 valve stem and thereby moving said valve toward or away from its seat, substantially as described.
5. Valve mechanism of the character described, comprising a casing partitioned by 50 a transverse wall, provided with a threaded bore, said wall separating said casing into an upper and a lower housing, the lower housing comprising a partially threaded packing compartment, a valve seating com- 55 partment and an intermediate fluid holding compartment, an apertured guide member threaded to engage the screw threads of said packing compartment and forming both an adjustable lower gland for said packing 60 compartment, and a top closure for said fluid compartment, packing material mounted above said gland, a plug screwed into the lower end of said lower housing and pro- 65 vided with a central chamber on its upper side, an annular passage on its periphery and ducts connecting said central chamber with said annular passage, an axially per- 70 forated disk provided with a valve seat mounted above said plug, said casing being provided with an inlet for fluid located above said valve seat, and an outlet for fluid registering with said annular passage, and a valve stem having a screw threaded head 75
- said casing below said valve seat, and a valve stem extending through said gland and said packing and having a screw threaded head engaging with said threaded wall bore, a plug valve carried by said valve stem coaxing with said valve seat, in combination with means for moving said valve comprising a lock mounted in said upper housing and engaging the head of said valve stem, substantially as described. 80
6. Valve mechanism of the character de- 85 scribed, comprising a casing partitioned by a transverse wall, provided with a threaded bore, said wall separating said casing into an upper and a lower housing, the lower 90 housing comprising a partially threaded packing compartment, a valve seating compartment and an intermediate fluid holding compartment, an apertured guide member threaded to engage the screw threads of 95 said packing compartment and forming both an adjustable lower gland for said packing compartment, and a top closure for said fluid compartment, packing material mounted above said gland, a ported valve seat closing the outer end of said fluid compartment, an inlet for said fluid compartment above said valve seat, and an outlet leading from 100 said casing below said valve seat, and a valve stem extending through said gland and said packing and having a screw threaded head engaging with said threaded wall bore, said head being provided with a trans- 105 verse slot at its upper end, in combination with means for moving said valve comprising a lock mounted in said upper housing and having a downwardly projecting lug engaging in said slot in the head of said valve stem, substantially as described. 110
7. Valve mechanism of the character de- 115 scribed, comprising a casing partitioned by a transverse wall, provided with a threaded bore, said wall separating said casing into an upper and a lower housing, the lower housing comprising a partially threaded 120 packing compartment, a valve seating compartment and an intermediate fluid holding compartment, an apertured guide member threaded to engage the screw threads of said packing compartment and forming both an adjustable lower gland for said packing 125 compartment, and a top closure for said fluid compartment, packing material mounted above said gland, a plug screwed into the lower end of said lower housing and pro- 130 vided with a central chamber on its upper side, an annular passage on its periphery and ducts connecting said central chamber with said annular passage, an axially per- forated disk provided with a valve seat mounted above said plug, said casing being provided with an inlet for fluid located above said valve seat, and an outlet for fluid registering with said annular passage, and a valve stem having a screw threaded head 135

engaging said threaded wall bore, said head being provided with a transverse slot at its upper end, in combination with means for moving said valve comprising a lock mounted in said upper housing and having a downwardly projecting lug engaging in said slot in the head of said valve stem, substantially as described.

8. Valve mechanism of the character described, comprising a casing partitioned by a transverse wall, provided with a threaded bore, said wall separating said casing into an upper and a lower housing, the lower housing comprising a partially threaded packing compartment, a valve seating compartment and an intermediate fluid holding compartment, an apertured guide member threaded to engage the screw threads of said packing compartment and forming both an adjustable lower gland for said packing compartment, and a top closure for said fluid compartment, packing material mount-

ed above said gland, a plug screwed into the lower end of said lower housing and provided with a central chamber on its upper side, an annular passage on its periphery and ducts connecting said central chamber with said annular passage, an axially perforated disk provided with a valve seat mounted above said plug, said casing being provided with an inlet for fluid located above said valve seat, and an outlet for fluid registering with said annular passage, a valve stem having a screw threaded head engaging said threaded wall bore, and a plug valve carried by said valve stem coating with said valve seat, in combination with means for moving said valve comprising a lock mounted in said upper housing and engaging the head of said valve stem, substantially as described.

In testimony whereof, I affix my signature.

ADELBERT R. WICKER.
